No. 36,535.

Patented September 8, 1903.

UNITED STATES PATENT OFFICE.

EUSTACE CREEES AND CHARLES S. COURT, OF PROVIDENCE, RHODE ISLAND,
ASSIGNORS TO THE WATSON AND NEWELL COMPANY, A CORPORATION
OF RHODE ISLAND.

DESIGN FOR A HANDLE FOR SPOONS, FORKS, OR SIMILAR ARTICLES.

SPECIFICATION forming part of Design No. 36,535, dated September 8, 1903.

Application filed August 14, 1903. Serial No. 169,540. Term of patent 7 years.

To all whom it may concern:

Be it known that we, EUSTACE CREEES and CHARLES S. COURT, citizens of the United States, residing in Providence, in the county of Providence and State of Rhode Island, have invented a new, original, and ornamental Design for the Handle of a Spoon, Fork, or Similar Article, which is illustrated in the accompanying drawings, forming part of this specification.

Figure 1 represents the obverse, and Fig. 2 the reverse, face of the design, which is executed in relief.

What we claim is—

The ornamental design for the handle of a spoon, fork or similar article as shown.

In testimony whereof we have signed our names in the presence of two witnesses.

EUSTACE CREEES.
CHARLES S. COURT.
